UNITED STATES PATENT OFFICE

2,452,997

RECTAL SPRAY DEPURATOR

William Jennings Coward, Lakeland, Fla.

Application February 26, 1946, Serial No. 650,343

2 Claims. (Cl. 128—231)

1

This invention relates to a rectal spray depurator.

An object of the invention is the construction of a novel and efficient device to be used by sufferers of piles, hemorrhoids, fistulas, pruritis ani and any rectal soreness intensified by the present way of cleaning one's self after a bowel evacuation.

Another object of the invention is the construction of an efficient device which will eliminate pain, and bleeding, brought on by the rubbing and smearing with the toilet paper wiping process.

A still further object of the invention is the construction of a novel device that can be easily assembled, and operated by the user.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in side elevation, a small part being shown in section, of a device constructed in accordance with the present invention, while

Figure 2 is a top plan view thereof.

Figure 3 is an enlarged fragmentary, vertical sectional view of the device.

Figure 4 is an enlarged sectional view taken on line 4—4, Figure 1.

Figure 5 is an elevated rear view of the U-shape guard, which is open at its bottom.

Referring to the drawings in which the preferred embodiment of my invention is illustrated, 1 is a rigid hollow arm substantially curved throughout its length for the purpose hereinafter specified. A fitting 2 extends into the upper end of hollow arm 1 (Fig. 3) and on the outer end of fitting 2 is a rubber bulb 3. A rubber tubing 4 is in the hollow arm 1 with the inner end of fitting 2 extending into said rubber tubing 4.

A comparatively stiff rubber guard 5 is provided; this horizontal guard 5 is open both at its top and bottom, and is substantially U-shape and is provided with an upper saddle edge 6 and a pommel 7. The guard 5 is provided with parallel lips 8 that fit against the sides of the hood 9 (Fig. 4), and through these lips 8 and hood 9 extend screws 10. These screws also extend into the hollow arm 1 thereby holding the guard 5 and hood 9 upon the arm 1. By this connection, the guard 5 is adjustably mounted upon the lower end of hollow arm 1. The hood 9 is provided with an elongated slot 11 through which spray nozzle 12 extends. This nozzle 12 is carried by the lower end

2

of the rubber tubing 4. The hollow arm 1 is provided with two V-shape slots 13 (Figs. 2 and 4), so that the nozzle 12 is allowed some movement within the hood 9, which allows the nozzle to oscillate approximately one-eighth turn each way from straight up, when desired.

It is to be understood that the rubber bulb 5 is self-expanding and that the hollow arm 1 constitutes a housing for the rubber tubing 4. 10 When the guard 5 is in place against the rectum, it forms a collar around the area to be cleaned, and prevents any fluid or matter escaping beyond it. The guard 5 can be made of any rubber composition, plastic or metal, and is shaped to 15 ordinarily fit the contour of the rectum when the user is in a sitting position. The pommel portion 7 of the guard extends upward to fit into the indentation of the buttocks at the base of the spine; this also serves to direct the guard to proper location. The rubber bulb 3 is preferably of ten or twelve ounce fluid capacity.

In operation, the bulb 3 is detached and filled with fluid from a prepared vessel (warm water or other with or without antiseptic as desired). 25 The device is then carried by the user to the toilet. The bowel evacuation is completed. By reason of the curved structure of the hollow arm 1, the guard 5 is allowed to be placed between the legs of the user, and then the guard is placed 30 back beneath the rectum, with the perforated nozzle 12 beneath the anus. The user pulls the guard 5 upward against the buttocks with one hand, the saddle edge 6 and the pommel 7 fitting the user excellently, and then the user squeezes the bulb with his free hand. The water is forced 35 out of the spray nozzle 12 at the desired force of the user in spurts or steady. As the user squeezes the bulb he oscillates the spray, thereby cleaning the entire area from side to side. When pressure 40 is relieved off the bulb 3 it expands, and by repeating pressure on bulb it is easy to force every drop of fluid therefrom. A refill of the bulb from the vessel can be accomplished by user should it be necessary. After the wash-off, the rectum 45 can, if desired, be "blotted" dry with toilet paper. Thus the rectum is treated gently, cleaned thoroughly, and to the diseased rectum a painful operation is eliminated.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such altera-

tions or changes as shall fairly fall within the scope of the appended claims.

What I claim is:

1. In a rectal spray depurator, the combination of a horizontal substantially U-shape guard open at its top and bottom and provided with vertical sides only and with parallel vertical lips at one end, a hood provided with a vertical elongated slot at its outer end, said hood positioned between said parallel lips, a hollow arm provided with V-shape slots in its inner end, said hollow arm extending into said guard parallel with said lips, means fastening said lips, guard, and hollow arm together, a tubing in said hollow arm and being capable of slight movement within said V-shape slots, said tubing extending at its inner end into said hood, a nozzle within said horizontal guard, and attached through said elongated slot to the inner end of said tubing, whereby said tubing and nozzle is permitted to have a slight movement within said guard, and a bulb connected to the outer end of said tubing.

2. In a rectal spray depurator, the combination of a curved hollow arm, said arm provided with a pair of V-shape slots on its lower end, a rubber tubing movably mounted within said hollow arm and extending at its lower end beyond the lower end of said arm, a fitting on the upper end of said rubber tubing and extending beyond the upper end of said hollow arm, a rubber bulb on the outer end of said fitting, a hood positioned horizontally on the lower end of said hollow arm, said hood provided with a vertical elongated

slot, a substantially U-shape horizontal guard provided with parallel lips at its open end, said parallel lips bearing against portions of said hood, screws extending through said lips, hood, and into said hollow arm, said horizontal guard being open at its top and bottom and provided with an upper saddle edge and with a raised pommel at its outer end, a spray nozzle within said guard, and extending through said elongated slot of said hood and mounted upon the lower end of said rubber tubing within said hood, whereby the operator by grasping said rubber bulb can cause slight movement of the inner end of said rubber tubing and nozzle within said hood, substantially as shown and described.

WILLIAM JENNINGS COWARD.
